(57)

CLAIM

The ornamental design for an ammunition magazine, as shown and described.

DESCRIPTION

FIG. 1 is a front perspective view showing the new design;
FIG. 2 is a rear perspective view thereof;
FIG. 3 is a front elevation view thereof;
FIG. 4 is a rear elevation view thereof;
FIG. 5 is an elevation view of the right side thereof;
FIG. 6 is an elevation view of the left side thereof;
FIG. 7 is a top plan view thereof; and,
FIG. 8 is a bottom plan view thereof.

Dashed lines, and the structures they depict, form no part of the claimed design.

1 Claim, 6 Drawing Sheets
